United States Patent Office

Des. 183,330
Patented Aug. 5, 1958

183,330

PLASTIC SHEET MATERIAL OR SIMILAR ARTICLE

Arthur D. Sylvester and Arno H. Scheiding, Rowayton,
Conn., assignors to L. E. Carpenter & Co., Inc., Whar-
ton, N. J., a corporation of New Jersey

Application January 29, 1957, Serial No. 44,642

Term of patent 14 years

(Cl. D87—3)

Fig. 1.

Fig. 2.

Fig. 1 is a plan view of a piece of plastic sheet ma-
terial embodying our new design and showing a com-
plete repeat thereof; and

Fig. 2 is a vertical sectional view, taken along line
II-II of Fig. 1.

We claim:

The ornamental design for a plastic sheet material or
similar article, substantially as shown.
